UNITED STATES PATENT OFFICE.

JOSEPH KREBS, OF BEDFORD HILLS, NEW YORK.

CLOTHES-HANGER.

1,318,290.

Specification of Letters Patent. Patented Oct. 7, 1919.

Application filed May 10, 1919. Serial No. 296,227.

To all whom it may concern:

Be it known that I, JOSEPH KREBS, a citizen of the United States, and a resident of the city of Bedford Hills, county of Westchester, and State of New York, have invented a new and Improved Clothes-Hanger, of which the following is a full, clear, and exact description.

This invention relates to clothes hangers. More particularly the invention appertains to clothes hangers and hat hooks which may be secured to cylindrical objects and so grouped about the object as to permit clothes and hats to be hung thereon for the purpose 15 of drying.

A broad object of my invention is to provide a hat and clothes hanger which is installed upon the ordinary type of water heating boiler usually found in the home.

An object of the invention is to provide a clothes and hat hanger and rack which will be clamped upon a water heating boiler for holding clothes adjacent the boiler such that heat radiating from the boiler will be 25 utilized for warming and drying clothes.

With the above and other objects in view my invention has relation to a certain arrangement and combination of parts, an example of which is described in the following 30 specification, pointed out in the appended claims and illustrated in the accompanying drawings, wherein:

Figure 1 illustrates a plan view of the hat and clothes hanger applied to a water heating boiler.

Fig. 2 shows a sectional view taken upon the line 2—2 of Fig. 1, and illustrates a hat hook embodied as a part of my invention.

Fig. 3 is a sectional view taken upon the 40 line 3—3 of Fig. 1 showing the clothes hanger rod in detailed view.

Fig. 4 shows a detailed sectional view taken upon the line 4—4 of Fig. 3.

Fig. 5 illustrates a form of adapter link 45 used in connection with my invention.

Referring now more in particular to the drawings, the numeral 1 points out any cylindrical device upon which it may be desired to install the hat and clothes hanger 50 and rack comprising this invention, and in particular points out a water heating boiler of the domestic type usually found in the home. The boiler is usually connected up with the heating range, or provided with other suitable means for heating the water. The water heating boiler generally comprises

substantially a large vessel capable of holding a sufficient quantity of water for lasting a family or families for a considerable period and when the water thereof is heated this boiler radiates an adequate supply of heat for drying clothes. My invention particularly relates to means for utilizing this heat in drying clothes and other household utilities.

A band of chain or other suitable material 2 encompasses the boiler and is used as the basis for supporting the several clothes hanging racks and hooks. This chain band is provided with clamp brackets 3 attached to each end thereof. A bolt 4 joins the clamps together and tightens the chain band upon the boiler.

A plurality of clothes hanging rods 6 are supported by the chain band and radiate 75 from the boiler. A number of hat hooks 7 are fitted to the chain band and project from the boiler for the purpose of receiving hats, coats or other articles to be hung thereon.

A feature of this invention resides in the 80 particular form of attachable and detachable, and foldable hanger rod and coat hook. The inner end of the rod is fitted with a metal bracket comprising an extended arm 8 integrally formed with a hook 9. The 85 extended arm is provided with an open clamp ring 10 such that the rod may be introduced into the opened members 10 after which they will be tightly closed there-around securing the rod to the bracket. A 90 screw 11 may be used to secure the rod to the bracket, or it may be preferable to employ a small sharp barb made integral with the metallic fixture and adapted to embed itself in the wooden rod.

The chain band 2 comprises a well known form of sprocket chain links of the detachable type, such that the length of the chain band can be increased or decreased for fitting around different sized boilers. The 100 chain band will be provided with a form of adapter link 14 for the purpose of receiving the particularly designed fitting employed in connection with the clothes hanger rod and hat hooks. This adapter link is shown 105 in Figs. 4 and 5, and comprises a link body portion 14 having a loop 15 integrally formed therewith, the cylindrical body 15 of the loop ranging parallel with and spaced apart from the cylindrical body 14. A pair 110 of upstanding spaced lugs 16 are integrally formed on the other body opposite to the

loop of the link, and are spaced apart substantially equal to the length of the opening of the loop. The hook 9 of the attachment fixture supporting the rod is inserted into 5 the loop of the adapter link such that the lower portion of the hook rests in contact against the opposite body of the link and between the upstanding lugs 16. This causes the clothes hanger rod to be maintained in an outstanding horizontal position 10 and very substantially fixed upon the boiler for holding a heavy weight of clothing or other material. The rod can be easily and quickly removed from the adapter link or 15 it may be folded downwardly in position adjacent the wall of the boiler as indicated in dotted lines. Thus the rod can be either removed or folded down out of the way when not in use.

20 The hat and coat hook 7 is designed to fit upon the same adapter link. The hook 7 is in integral formation with a hook fixture 17. The hook 7 is confined in service position as illustrated by hooking over the 25 loop of the adapter link and lying between the lugs thereof. These lugs function to confine the hook 7 and rod 6 in proper position, and prevent their lateral displacement or movement relative to the supporting band or chain. This hook can be removed at will in a similar manner to the removal of the aforescribed rod.

30 This form of clothes and hat hanger will adequately fill a long-felt want for household utility devices of this character. It can 35 be inexpensively produced and put to great

advantage in rainy weather for drying out clothes and household articles.

Having thus described my invention, what I claim as new, and desire to secure 40 by Letters Patent is:

1. In a clothes hanger device, comprising in combination; a section of chain links, adapter links employed in the chain section, a rod, an attachment fixture carried on the 45 rod and inserted in the adapter link.

2. A clothes hanger rack to be secured upon a water boiler, comprising in combination; a section of chain, adapter links employed in the section of chain, a loop formed 50 on the adapter link, a hook fixture inserted in the loop of the adapter link, and a rod attached to the fixture.

3. A clothes hanger device for installation upon a water boiler, a section of chain, 55 clamp brackets attached to the chain for clamping the section of chain around a water boiler, an adapter link, a loop formed on the adapter link, lugs formed on the adapter link opposite the loop, a rod, and a 60 hook formed on the rod to be confined in position within the loop and between the lugs.

4. In a hat and coat hanger for use in connection with a water boiler, comprising in combination; a band clamped upon the 65 water boiler, an adapter carried by the band, a loop formed on the adapter, a set of lugs integrally formed on the adapter opposite the loop, a clothes hook, and a supporting hook suspended from the loop and confined 70 between the lugs.

JOSEPH KREBS.
